UNITED STATES PATENT OFFICE.

FRANZ IFFLAND, OF BERLIN, GERMANY, ASSIGNOR TO CARL RAKENIUS & CO., OF SAME PLACE.

DESIGN FOR A LAMP.

SPECIFICATION forming part of Design No. 18,934, dated February 19, 1889.

Application filed November 16, 1888. Serial No. 291,067. Term of patent 7 years.

To all whom it may concern:

Be it known that I, FRANZ IFFLAND, a subject of the King of Prussia, German Emperor, and a resident of the city of Berlin, Prussia, German Empire, have invented and produced a new and original Design for a Lamp, of which the following is a specification.

This design appears in the photograph.

The leading feature of my design consists 10 of the representation of an ape with his two arms embracing and carrying a cocoanut and making a grimace, as if he did not like to give it back again. At the top of the cocoanut there is a round aperture. This figure rises 15 from a circular base resting upon four leaf-shaped feet, such base having an upper and lower recess or neck, between which there is a swelling representing leaves kept together by broad bands. Upon this circular base 20 rests a flat vaulted stratum of earth, somewhat extending beyond the upper surface of the base. An ape of a middling size, the body upright, kneels with his right leg upon the earth, showing backward the whole surface of the sole of the foot, while with his left leg, 25 the foot of which, with outward-spreading toes, firmly stands against the soil, he assumes a squatting posture, the tail from behind lying on the ground round the left foot and extending in an inward curve toward the knee of the 30 right foot. The head of the ape is turned to the left and the body backward and on the left side bent inward. On the right side, before him, the ape keeps with his arms a cocoanut leaning against his shoulder and head in 35 a horizontal position, the flattest side of the nut being turned upward.

I claim—

The design for a lamp, as shown and described, consisting of the body representing a 40 cocoanut, the standard representing an ape, and the circular base having the recesses and ornamentation shown.

FRANZ IFFLAND.
